HEAT EXCHANGER FOR PRODUCING
GRANULAR SALT PRODUCTS

Emory W. Douglass and Parker S. Dunn, Carlsbad, N. Mex., assignors to Potash Company of America, Denver, Colo., a corporation of Colorado

Application December 20, 1948, Serial No. 66,388

1 Claim. (Cl. 257—116)

1

Our invention is directed to apparatus for the treatment of finely divided salts and more specifically to apparatus of the type adapted to create a granular Crystallite material of predetermined size. Reference is made to our copending application Serial No. 607,172, filed July 26, 1945, now abandoned, which described but does not claim similar apparatus.

Our invention is particularly adapted for use in treating potash salts such as those obtained from underground deposits mined near Carlsbad, New Mexico, but it should be understood that the apparatus herein disclosed is also adaptable for use in connection with other salts of similar nature.

Fine particles of potassium chloride and similar salts are particularly objectionable not only because of the dust hazard, but also because they exhibit a markedly greater hygroscopicity than coarser particles of the same material, this being generally true of other similar salts. When such salts are exposed for any extended period of time to a relatively moist atmosphere they tend to cake, which increases the difficulty encountered in handling and in some instances reduces the utility of the product by reducing its rate of solution or reaction.

A primary object of our invention is to provide apparatus for economically converting fusible salts, particularly potash salts containing a substantial percentage of fines, into granular Crystallite particles having a minimum percentage of fines, and having a relatively low hygroscopicity.

Other objects of major importance include the provision of an improved salt-fusing furnace adapted to partially refine the salt molten therein; the provision of novel salt-cooling means adapted to continuously cool molten salt discharged from our furnace at a rate sufficiently rapid to substantially prevent the formation of crystals or the segregation of salt components; the provision of salt-cooling means which discharges the solidified salt as relatively coarse flakes having one predetermined dimension; the provision of an improved cooler conveyor discharging the flaked product into a crusher and the provision of apparatus for establishing a complete cycle of treatment for undersized material or fines.

These as well as many additional objects and important advantages of my apparatus will be clearly understood from the following detailed description and from the appended drawings in which:

2

Fig. 1 is a diagrammatic view showing the flow of material through our apparatus;

Fig. 2 is a partially sectioned elevation of our cooling device;

Fig. 3 is a plan view of our cooling device illustrating the relationship of our device to the furnace;

Fig. 4 is an elevation of our cooling device;

Fig. 5 is a partially sectioned elevation of our furnace; and

Fig. 6 is a partially sectioned elevation of our cooler conveyor.

Our apparatus in brief includes a furnace having a trough-shaped floor sloping towards a discharge spout which is disposed somewhat above floor level and above a cleaning spout through which impurities may be periodically eliminated. The refined salts, as for example the salts received from froth flotation treatment, are discharged through suitable openings in the roof of the furnace to form spaced conical piles along the sides of the trough-shaped furnace bottom. As the material on the surface of the cones melts it forms a pool which eventually reaches a sufficient depth to flow from the discharge spout onto a hollow rotating table which is cooled by water circulated internally through the table. This rotating table cools the molten salt very rapidly, the speed of cooling being sufficient to substantially prevent the formation of crystals in the material. The solidified salt is removed from the table by a conveyor disposed extending partially across the surface of the table and having a series of transverse table-engaging flights which rake the fused salt from the table surface.

The initially crushed salts fall into a spiral conveyor through which a current of cool air is passed to reduce the temperature of the material to a point where it may be readily crushed. Since the air passing through this conveyor picks up considerable dust, it is passed through a suitable separator and the precipitated particles recycled through the furnace. The conveyor discharges into a suitable crusher which delivers ground salts to screens, where the coarse particles are recycled to the grinder, the fine particles recycled to the furnace, and the particles of the desired size ranges segregated for packaging. Thus it may be seen that none of the fine product is wasted and that the type of product produced is by its nature much less hygroscopic than the salt in its natural form. It has also been found that the mechanical strength of the particles, i. e. their resistance to crushing is substantially increased, thus permitting more severe handling of the

product without damage. Since all of the apparatus is adapted for continuous operation, very little labor is required in the processing of the material.

Furnace

Referring to Figs. 1 and 5, we provide a melting furnace having bed 10 and refractory upright side walls 11 supporting a curved roof 12. Within the furnace, generally designated 14, is a trough-shaped floor 13 which slopes towards the discharge end of the furnace. The roof 12 is provided with a series of openings 16 communicating with hoppers 17 through which salts, as for example sylvite ore from a floatation treatment, may be fed. The openings 16 are above the portion of the floor 13 lying adjacent the side walls 11, and are spaced a distance sufficient to permit the salts to form a series of conical piles indicated at 18. Preferably the spacing is such that the peripheries of these piles are only slightly overlapping, thus avoiding the formation of a relatively continuous ridge of salt along the boundaries of the furnace floor 13.

The furnace 14 is also provided with an end wall 19 having an exhaust opening 24 for gases communicating with a stack 22. From the end wall 19, the furnace floor 13 slopes downwardly towards the discharge end wall 23 of the furnace which is provided with a lower spout 24 and a discharge spout 26, as well as an inspection door 27. The lower spout 24 slopes in the same direction as the floor 13, but is at a somewhat more abrupt angle and is adapted to tap the lower portion of a pool 28 of molten salt, which forms near the wall 23. Normally the spout 24 is plugged and is opened only infrequently to discharge impurities which collect in the lower portion of the pool 28. The discharge spout 26 is normally disposed above the lower discharge spout 24 and determines the depth of the pool 28. In operation, the spout 26 is normally open and discharges into a trough 29, which delivers molten salt to a cooling table, generally designated 31. The furnace 14 may be fired by gas, oil, powdered coal or the like, gas being preferred for convenience of operation and cleanliness.

Burners 32 are preferably disposed in the end wall 23 and are adapted to deliver a blast of hot gas across the piles 18 of salt, the combustion products being eventually discharged through the opening 21 into the stack 22. As the salt on the surface of the piles 18 melts, it flows down the sloping floor 13 of the furnace 14 to form the pool 28.

Cooling table

The cooling table 31 is illustrated in Figs. 2, 3, and 4 and includes a table 33 of substantial diameter mounted for rotation, as on a shaft 34. Although several different methods for mounting and driving the table 33 may be adopted, we prefer to provide the vertical shaft 34 with a collar 36 upon which a thrust bearing may be mounted. The table 33 is hollow and includes an upper plate 37 and a lower plate 38 joined together by a peripheral wall 39. The upper plate 37 may in most instances be flat, but if desired may be dished very slightly towards the center of rotation to assist in preventing accidental spilling of the molten salt discharged from the trough 29. The elevation of the edges of the plate 37 should, however, in this modification not exceed two inches with respect to the center of the table when the diameter of the table is approximately twenty-four feet.

The upper plate 37 is joined to a cylindrical upright flange 41, while the lower plate 38 is joined to an inner cylindrical upright flange 42 disposed within and concentric with the flange 41. A plurality of radially extending pipes 43 are secured to the inner flange 42 and extend outwardly between the upper and lower plates 37 and 38 to a point near the peripheral wall 39. Cooling water may therefore be fed by a pipe 45 into a well 44 defined by the inner flange 42 and flow outwardly through the pipes 43 for discharge into the hollow table 33 near its edge. A discharge pipe 46 extends upwardly through the lower plate 38 into a well 47 defined by the inner flange 42, the outer flange, and the lower plate 38, the height of the pipe 46 above the lower plate 38 defining the maximum elevation of cooling water in the discharge well 47. The discharge pipe 46 rotates with the table and discharges cooling water which may be fed to the system through pipe 45 into a circular trough 43 disposed below the end of the discharge pipe 46 and which communicates with a sewer or other suitable disposal means.

25 A circular flange 49 is secured to the under side of the lower plate 38 and is grooved around its periphery to receive the belt 51 engaging the output pulley of a variable speed-speed reducer 53, which may in turn be driven by a suitable motor 54.

30 A plate 56 may be disposed across the lower surface of the flange 49 and supports circular flanges 57 to which a circular rail 58 is attached. A hollow circular base 59 is mounted on the floor and rotatably supports a plurality of flanged wheels 61 upon which the rail 58 rests.

35 The discharge spout 29 is arranged to deliver molten salt to table 33 at a point intermediate the center of rotation and circumference, the spout 29 being preferably inclined in the direction of rotation of the table. The size and speed of rotation of the table 33 are correlated with the cooling capacity of the table and the rate of discharge of molten salt from the furnace to quickly solidify the molten salt as it strikes the table 33 and spreads out into a thin relatively even layer. Therefore when the salt has traveled through 180-270 degrees of rotation, it will be solidified and will tend to crack in vertical planes due to the contraction of the salt upon solidification.

40 To remove the solidified salt from the table 33, we provide a scraper, generally designated 62, comprising a frame 63 extending partially over the table 33 and terminating at or near the periphery of the flange 41. Sprockets 64 are mounted on a shaft 65 journaled in the frame 63 near its extremity and support chains 67 to which a plurality of spaced laterally extending flights 68 are secured. By proper disposition of the frame 63 the flights 68 are caused to engage the surface of the table 33 while the chains 67 are being driven by suitable means, thus continuously flaking the solidified salt from the surface of the table 33 and drawing the granular material across the surface of the plate 33 to a suitable receptacle or discharge hopper 69 disposed under the scraper 62 and near the periphery of the table 33.

45

50

55

Cooler conveyor

60 It should be understood that the granular salt product discharged from the table 33 into the hopper 69 is only slightly below the solidification point of the mixture and substantially above 65 room temperature with the result that its fri-

ability is not at a maximum. It is therefore desirable to cool the relatively coarse salt flakes before crushing to the desired size. For this purpose we provide a cooler conveyor, generally designated 71, comprising a cylinder 72 having spiral flights 73 mounted within. The cylinder 72 is rotatably supported in an inclined position by bearings 74 and is rotated by a motor 76 having a shaft 77 engaging a bevel pinion gear 78 which meshes with a ring gear 79 secured to the cylinder 72. The conveyor 71 discharges into a hopper 81 disposed above a suitable crusher 82.

To cool the salt passing through the conveyor 71 we provide a blower 83 or other suitable source of draft near the discharge end of the conveyor 71, and preferably communicating with the interior of the conveyor 71 through an opening 84 having a plurality of downwardly sloping baffles 86 disposed above the hopper 81. The hopper 69 is provided with a deflector 87 extending downwardly into the hopper 69 near the charging end of the conveyor 71, the function of the deflector 87 being to divert a major portion of the air passing through the conveyor 71 into a vent pipe 88, which communicates with a suitable cyclone or similar separator 89. Solid particles separated from the air in the separator 89 are recycled to the hoppers 17 for remelting. Thus it may be seen that the dust or fines generated in the conveyor 71 or in the crusher 82 will be conveyed to the separator 89 and remelted for further processing.

Crusher and screens

The crusher 82 may be of any type suitable for operation on material such as salt, as for example an impact crusher and discharges from a spout 91 on to screens 92, where the ground product is divided into undersize material, standard size material, granular material, and oversize. The oversize material passes over the screens 92 into a trough 93, where it is elevated by suitable bucket conveyor 94 and discharged through a spout 96 into the hopper 81 for regrinding. The granular material, which may, for example, be of a size passing through a six mesh screen, but retained on a twenty mesh screen, is discharged into a hopper 97 communicating with a conveyor 98. The standard size material, which may for example pass through a twenty mesh screen but may be retained on a sixty-five mesh screen discharges into a hopper 99 communicating with a conveyor 101. Material smaller than the desired minimum size may be discharged into a hopper 102 and conveyed by suitable means through a pipe 103 to either the separator 89 or the hoppers 17 on the furnace 14 for remelting.

Operation

It is customary today to refine the relatively impure salts by froth flotation in known manner, which usually requires reduction of the salt to a relatively small particle size. The purified and treated salt from the froth flotation process or such portion of it as is desired is delivered to the hoppers 17 on the furnace 14 and there mixed with the undersized material or fines delivered to the hoppers 17 through the pipe 103, or from the separator 89. The fine material may be either continuously or intermittently fed to the furnace from the hoppers 17 through the openings 16 to form the conical piles 18 near the walls 11 of the furnace. The heat reflected by the walls of the furnace plus the direct heat 75

from the burners 32 melts the salt on the surface of the piles 18, which flows along the sloping trough-shaped floor 13 of the furnace to form a pool 28. Since the material to be melted is disposed in a series of conical piles rather than in the form of a continuous ridge, a greater surface area is exposed to the heat and the molten material is continuously delivered to the pool 28, thereby preventing insulation of the unmolten material at the base of the cones. The pool 28 is quiescent and permits a settling of various particles having a high specific gravity. These impurities collect in the bottom of the pool near the lower spout 24 and may be periodically discharged. Preferably the amount of heat delivered to the furnace is sufficient to maintain the molten material in the pool 28 at a point only slightly above its solidification point. In the case of potash salts this is particularly desirable since the molten material is very mobile in nature and tends to flow very easily.

The molten salt is preferably continuously discharged from the furnace 14 to the table 33 in such manner as to spread the molten salt in a relatively even layer across the working surface of the table 33, the thickness of the layer of salt preferably being on the order of about an eighth of an inch. The temperature and quantity of the cooling water introduced through the pipe 45 and circulated through hollow table is correlated with the speed of rotation of the table 33 and is sufficient to very rapidly drop the temperature of the molten salt mixture to a point below its solidification or freezing point, thus substantially preventing the formation of crystals and the segregation of components in the salt. In the case of a potassium chloride salt containing 95-98% KCl we prefer to maintain as closely as possible a discharge temperature at the spout 29 of 755° C. The cooling capacity of the table 33 must therefore be sufficient to reduce this temperature approximately five degrees centigrade in a short period of time, since at the latter temperature the salt will be in a solid condition.

As the salt cools on the table 33 it contracts and shatters into relatively large flakes defined by relatively vertical and irregular planes of fracture extending through the material to the surface of the table 33. These flakes are easily removed by the scraper 62 and delivered through the hopper 69 to the cooler conveyor 71. Although the salt flakes are at this point solid, the temperature is still relatively high, which renders the flakes somewhat less friable than is desirable for grinding or crushing. The air passed through the conveyor 71 by the blower 83 reduces the temperature of the salt flakes to a satisfactory point and eliminates a substantial percentage of the fines which would otherwise be delivered to the crusher. It will be understood that since the discharge of the conveyor 71 communicates directly with the hopper 81 or the grinder 82, all the dust and fines escaping from the grinder 81 will be picked up by the draft sweeping through conveyor 71 and delivered by the vent 88 to the separator 89 for reprocessing.

The crusher 82 is operated at a rate somewhat in excess of its capacity to reduce the percentage of fines formed in the operation, the crushed or oversized material being recycled through the conveyor 94 to the crusher 82 for reprocessing.

It is to be particularly noted that all of the fines formed at any stage of the operation are recycled to the furnace 14 for remelting, thus

reducing the dust losses in the system to a negligible minimum. Since the solidified salt is of a Crystallite nature, i. e., having a structure in which crystals are substantially non-existent, very few fines are formed in handling of the material and the crushed material exhibits very little tendency to its original powdered state. It may therefore be handled with very little difficulty, particularly when compared with similar material which has been briquetted and re-crushed. The major advantage, however, of this form of process is the reduction in the hygroscopicity of the material, which is markedly less than that of the same salt in any other known form.

We contemplate that those skilled in the art may wish to modify our apparatus in certain respects to meet operating conditions peculiar to various installations and we do not therefore specifically limit ourselves to the precise details herein disclosed except insofar as defined by the appended claim.

Having thus described the invention what is claimed is:

Apparatus for cooling molten materials, comprising a drum-type structure having a substantially flat upper surface and mounted for rotation about a substantially vertical axis, means including a central well portion on the upper surface of said drum, a partition in the well dividing the interior into an inner coolant supply chamber and an outer discharge chamber and a series of radial conduits extending from the supply chamber through the interior of the drum to a point of discharge adjacent the periphery

10

15

30

35

thereof for circulating the coolant between the inner and outer chambers, means for circulating a heat exchange medium through the interior of said structure and in contact with said flat surface, means for rotating said structure, means including an overhanging feed spout for feeding molten material onto said upper surface at a downward inclination and directed centrally of the drum, and a mobile scraper member disposed at more than 270 degrees from the point of feed introduction for peeling the matter congealed on the flat surface.
